ARTIFICIAL FISHING LURE

Robert K. Harris, Charlotte, N.C., assignor to
Ringley & Crockett, Inc., Charlotte, N.C.

Filed Sept. 27, 1974, Ser. No. 509,791

Term of patent 14 years

Int. Cl. D22—05

U.S. Cl. D22—28

FIG. 1 is a perspective view of the artificial fishing lure design of the present invention;

FIG. 2 is a top plan view of the artificial fishing lure of FIG. 1;

FIG. 3 is a side elevational view of the artificial fishing lure of FIG. 1, the opposite side being identical;

FIG. 4 is a bottom plan view of the artificial fishing lure of FIG. 1;

FIG. 5 is a front elevational view of the artificial fishing lure of FIG. 1; and

FIG. 6 is a rear elevational view of the artificial fishing lure of FIG. 1.

I claim:

The ornamental design for an artificial fishing lure, as shown and described.
